UNITED STATES PATENT OFFICE.

FRANCIS T. JOHNSON, OF CHICAGO, ILLINOIS.

DRIER.

Application filed March 2, 1922. Serial No. 540,422.

To all whom it may concern:

Be it known that I, FRANCIS T. JOHNSON, a citizen of the United States, residing at Chicago, in the county of Cook and State of Illinois, have invented a certain new and useful Improvement in Driers, of which the following is a specification.

My invention relates to improvements in heaters and driers, and particularly to an 10 easily constructed, simple, knock-down drier, which may be used for drying clothes. Among the purposes of my invention are the provision of such a drier, which will be cheap, efficient, and compact, and into which 15 the clothes may be easily placed. Another object is to provide such a drier in which a high degree of heat may be used without scorching or otherwise damaging the clothes therein dried. Another object is to provide 20 a drier with a minimum of moving parts. Another object is to provide a drier of which many uses may be made, and my drier is adapted for use not only as a clothes drier, but as a core drier, an enameling oven or a 25 heater. Other objects of my invention will appear from time to time in the course of the specifications.

I illustrate my invention more or less diagrammatically in the accompanying drawings, wherein:

Figure 1 is a front elevation with parts broken away;

Figure 2 is a section at 2-2 of Figure 1;

Figure 3 is a section at 3-3 of Figure 1;

Figure 4 is a section at 4-4 of Figure 1.

Like parts are indicated by like symbols throughout the specification and drawings.

A is a front wall of the heater, which is provided with any suitable door frames, A', with hinges A'', on which are swung door elements, each comprising a front face A''', and a rear face A''', spaced away therefrom. The doors are provided with opposed closing surfaces A''', A''', which are preferably broad and inclined to each other.

The hook B on the upper side of the door frame is adapted to be engaged by a rod B', pivoted as at B'' on one of the door elements and loosely confined by the straps or loops B'', B'''.

The back of the drier may be formed by a simple sheet or surface C, of metal like the rest of the drier. The sides are preferably doubled, the outer elements C', C'', serving as flues and the inner freely perforated elements C''', C''', allowing free access of air to

and from the interior of the drier. The member C' is open at the bottom and closed at the top, the inlet C'' serving as an air inlet. It may be direct from the room as shown, or the air may be taken from some outside sources, where it will not be polluted by dust, or any suitable filtering or screening means, not here shown, may be used. The member C'' is closed at the bottom, but open 60 at the top, as at C''', as an outlet for the moist air from the dried clothes. The air outlets through the member C'' may be masked by overhanging eaves or flaps D as shown in Figure 1, to prevent their being closed by 65 clothing being drawn thereagainst.

The members C'', C''', are further provided with a plurality of transverse bars D' which are slotted or notched to receive the transverse rods D'', the notches and rods being 75 staggered, there being three at one level, two at the next and three at the next, as shown in Figure 3.

Adjacent the bottom of the heating casing is an angle iron shelf E, which surrounds the 80 interior of the entire drier. Removably supported thereby is the plate or pan E', having an upturned peripheral rim E''.

Somewhat above this pan is supported a screen F, as for example, on the transverse bars F', the downwardly turned ends, F'', of which fit in the straps F''', mounted on the heater walls. The screen and supporting bars are both removable.

Beneath the plate E' are depending straps 90 G, G', upon which is mounted a perforated gas pipe or burner G''. This pipe is bent and the outer end thereof penetrates as at G''' through the wall of the heater casing, and is provided with a stop cock, as at G''. G''' 95 is a lighting hole, having a cover G''', and G'' is any suitable observation peep hole, preferably covered with mica. The entire structure may be supported out of contact with the floor, as for example, by the supports G'', 100 preferably integral with the frame of the entire structure.

It will be evident that while I have shown a working device and one which is in use, yet I do not mean to be limited to the details 105 shown, and many variations might be made in the number, size, shape and disposition of parts without departing from the spirit of my invention. I wish, therefore, that the drawings and descriptions be taken as in a 110 large sense diagrammatic.

The use and operation of my invention

are as follows: I provide a simple rectangular casing with a thin bottom compartment, having a heater within it, preferably a simple gas pipe burner. The gas may be 5 turned off or on from outside and a peep hole is provided to see whether or not it is burning properly. It may be lighted from the outside through the hole G⁵, but when not open that hole is closed and there 10 is no escape or waste of the heated air. The pan or plate over the heating element is removable for cleaning and it has above it a removable screen which protects the clothes from singeing contact with the heated plate. 15 A drying current of air is admitted at the bottom of one side of the drier and is distributed by a side flue along the whole device, some of it being sent through the heating compartment and the rest of it being 20 supplied to the interior of the drier through a plurality of perforations, being spaced in rows along the sides of the casing. This air passes through the interior of the drier and out through the other side and up the 25 flue shown at the right of Figure 1. The escape of the heated air through the perforations in the plate C⁴, adjacent the ends of the covering plate, insures a constant draft through the drier and dry air is constantly drawn therethrough. The heater 30 keeps the entire interior of the drier and the air which passes through it at a high temperature, and the result is a very quick drying, the heated moist air passing constantly up the flue C⁶ and being replaced 35 with dry air, which is constantly heated as it passes among the articles to be dried. The doors are of a broad swinging type and allow a maximum access to the interior, but 40 the escape of the heated air is minimized by stopping the doors midway the height of the drier. While they are opened, the opening may be partially screened, as for example by a sheet. The goods to be dried 45 are then inserted and laid over the supporting bars. As the bars are staggered, the articles hung on one row hang between the bars of the row next below. The bars may be removed for convenience of access to the 50 rear bars and the size of the doors and the drier is such that all the bars are easily accessible to the operator. The opposed lips of the two door leaves are inclined to each other in order to make a tight contact and 55 partly to provide a type of door which may be easily closed and which has no tight fitting parts to jam. Furthermore, there is a minimum risk of damaging any clothes which may be gripped between the broad 60 plate lips or bearing surfaces of the two leaves. The swinging latch shown is easy to open and easy to close. This door may be opened and closed with a minimum of time

and effort to minimize the escape of heated air or the entrance of cold air, which might 65 delay the drying operation.

I claim:

1. A drier comprising a clothes containing chamber, a heating chamber separate therefrom and directly therebeneath, a partition separating them, and a protecting screen spaced above said partition. 70
2. In a drier, a clothes containing chamber and a heating chamber and a partition separating them, and heating means supported beneath said partition, and a protecting screen spaced above said partition. 75
3. In a drier, a clothes containing chamber and a heating chamber and a partition separating them, and heating means supported beneath said partition, and a protecting screen spaced above said partition, 80 said heating chamber and means being entirely inclosed and an observation window therefor. 85
4. A drier comprising a drying chamber, a heating chamber separate therefrom, a removable partition separating them, and a protecting screen spaced above such partition. 90
5. A drier comprising a clothes containing chamber, a separate heating chamber therebeneath, a plurality of removable clothes supporting elements within said clothes chamber, and a plurality of transverse shelves adapted to support them, a plurality being mounted on each shelf, the supports of each shelf being staggered in relation to those on the adjacent shelves, the vertical distance between the supports 100 and the transverse shelves being substantially less than the average length of the articles of clothing normally supported thereby. 105
6. A drier comprising a clothes containing chamber and a heating chamber therebeneath, an air inlet flue at one side of the drier, an air outlet flue at the other side, and a plurality of air passages between said flues and the interior of the drier, said flues 110 extending substantially from top to bottom of the heating chamber, at each side thereof.
7. A drier comprising a clothes containing chamber and a heating chamber therebeneath; a door in the upper portion of the 115 clothes containing chamber, and a plurality of clothes supporting bars extending across said clothes containing chamber adjacent said door, the bottom of said door being substantially above the bottom of said clothes containing chamber. 120

Signed at Chicago, county of Cook and State of Illinois, this 28th day of February 1922.

FRANCIS T. JOHNSON.
